UNITED STATES PATENT OFFICE.

RALPH BROOKS VAUGHN, OF KINGSTON, PENNSYLVANIA.

STEAM-BOILER.

SPECIFICATION forming part of Letters Patent No. 499,948, dated June 20, 1893.

Application filed January 14, 1893. Serial No. 458,410. (No model.)

To all whom it may concern:

Be it known that I, RALPH BROOKS VAUGHN, a citizen of the United States, residing at Kingston, in the county of Luzerne and State of Pennsylvania, have invented certain new and useful Improvements in Steam-Boilers; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to steam boilers, and has for its object to produce a boiler in which the steam will be quickly generated with a small consumption of fuel, and will be dried in the furnace before being distributed, and to generally improve the construction of such a boiler so that it will be simple in construction and efficient in use; and to the accomplishment of the foregoing and such other objects as may hereinafter appear, the invention consists in the construction and in the combination of parts hereinafter particularly described and then specifically defined in the claims, reference being had to the accompanying drawings forming a part hereof, and in which—

Figure 1 is a vertical section through the boiler, on the line 1—1 of Fig. 2. Fig. 2 is a horizontal section on the line 2—2 of Fig. 1. Fig. 3 is a vertical section on the line 3—3 of Fig. 1; and Fig. 4 a section on the line 4—4 of Fig. 1.

In the drawings the letter A designates the walls of the furnace constructed preferably of brick or masonry and provided with the door B for feeding fuel to the fire grate C and with the door D opening into the ash pit E. The furnace is provided preferably with a metallic top F and is formed above the space over the fire grate with a chamber G for a purpose hereinafter described, which chamber is provided with the metallic top or cover H. The furnace is also provided with a bridge wall I which separates the fire chamber from the space or chamber J through which the products of combustion pass on their way to the escape or draft flue K, and this chamber J is provided with a metallic

plate or partition L just below the top of the bridge wall so as the better to concentrate the heat of the escaping products of combustion around the lower portion or legs of the water tube. Within the furnace are arranged a number of tubes M, the same being built up or nested to the number desired and arranged with the desired number side by side, there being illustrated in the drawings five tubes in each row, and five rows one above the other. It is preferred to arrange the several rows so that the tubes of one row will lie over the spaces between the row next below so as to bring the heat and products of combustion into contact with the tubes of each row by causing the circulation to pursue a circuitous course, thereby utilizing the greatest amount of heat before the products escape from the furnace.

The tubes are arranged so as to incline upwardly from their lower ends, and their upper portions are projected at an angle to their length so as to rise uprightly or vertically as shown at N, the upright portions N above the water line receiving the steam generated from the water in the tubes and lying within the chamber G so that the heat from the furnace which rises into the chamber G and by it confined around the portions of the tubes containing the steam will dry the steam in such portions of the tubes before it is allowed to pass to the distributing pipes. The tubes M are also arranged so that their lower ends will lie intermediate of the fire chamber and the exit or draft flue K so that the products of combustion will pass from the fire chamber to the lower ends of the tubes and around the same in passing to the draft flue K. By this arrangement I cause a direct draft from the fire chamber to the draft flue and around the lower ends of the tubes so that the strongest or most intense heat is applied where it will do the most effective work, that is, at or near the point where the water first enters the tubes. In order to more effectively concentrate the products of combustion around this end of the tube, I form a wall O over the top row of tubes adjacent to the chamber J as illustrated in Fig. 1 of the drawings so that the products of combustion in escaping are concentrated around and about the tubes at their lower ends and in the direct line of pas-

sage from the fire chamber to the exit or draft flue.

The lower ends of the tubes are each connected to a T P, and the several T's are connected to each other by nipples Q so that the several pipes of each row of tubes are connected together in order that there may be a communication between the several tubes of each row through the channel or chamber formed by the T's P coupled together as described. The upright or vertical portions of the tubes in the steam drying chamber are connected together in like manner as at the lower ends of the tubes by the T's P and nipples Q. The channels or chambers at the lower ends of the tubes formed by the T's as described are connected at opposite ends to T's R by nipples S, and the end T's R are connected to each other by nipples Q so as to form channels or chambers at opposite sides of the tier of tubes having communication with the transverse channels or chambers formed by the T's P. It will be observed that by this construction each row of tubes M has communication with the side channels or chambers formed by the T's R at opposite sides of the tier of tubes so that communication is not only had between all the tubes of the tier but each row of tubes M has communication with the side channels or chambers independent of the other rows of the tier of tubes. This affords a more direct flow of water from the supply to each row of the tier of tubes, and also affords a greater heating surface so that the water is more quickly heated after its entrance from the supply. The construction also admits of the parts being more readily detached and disconnected from one another when necessary from any cause, and any one of the several rows can be disconnected from communication with the others when desirable for any reason without interfering with the working of the other rows of the tier. It will also be observed that the point at which the water from the supply through the supply pipe U is admitted is nearer to the fire chamber than the other portions of the tier of tubes so that the strongest heat is applied where it is most needed, the lower ends of the upper rows of tubes being farther removed as the water is somewhat heated before it reaches them and consequently requires not so high a temperature of heat but still they are in the direct line of the products of combustion on their way to the draft flue K. By this arrangement I get the most effective heating of the water with the least consumption of fuel.

The upright or vertical portions N of the tier of tubes communicate through the channels formed by the T's at their ends with the T's V through the nipples W, the T's V being connected with each other by the nipples X. The series of T's V form a chamber into which the steam passes from the upright portions N of the tier of tubes and from this chamber the steam passes through a pipe

Y into the distributing pipe Z. It will be observed that the steam chamber or drum formed by the T's V as well as the upright portions of the tier of tubes is located in the steam drying chamber G so that the steam in the vertical portions of the tubes and in the steam drum is dried before its passage into the distributing pipe. It will be observed that the water line of the tier of tubes is below the steam drying chamber G so that the whole force of the heat confined in that chamber most effectually dries the steam in the upright portions of the tubes and in the steam drum located in that chamber.

A safety valve A' and a steam gage B' connect with the steam chamber or drum, and a water gage C' with the water tubes, all of which are applied in the usual way for the usual purposes.

I have described with particularity the details of construction of the several parts and the arrangement of parts which I have found in practice to give the best results, but it is obvious that changes may be made and the essentials of my invention be still employed.

Having described my invention and set forth its merits, what I claim is—

1. The combination with the furnace provided with a steam drying chamber over the fire box and above the water line and with the exit or draft flue in the opposite walls of the furnace to the location of the fire box and in a higher plane than said box, of the tier of water tubes inclining upwardly from their receiving ends and formed with upright portions extending at an angle to the inclined portions and above the water line into the steam drying chamber and communicating with the steam distributing pipe, the lower portions of the inclined tubes being arranged one above the other to form a tier rising from the fire box toward the draft flue, substantially as and for the purposes described.

2. The combination with the furnace formed with the chamber G above the fire box and the water line and with the chamber J having the draft flue K, and the lower bridge I and upper wall O between the fire box and chamber J, of the tier of inclined water tubes having their lower portions extending through the space between the bridge I and wall O into the chamber J, and their upper portions extending at an angle to the inclination of the tubes into the chamber G above the water line and communicating with the steam distributing pipe, substantially as and for the purposes described.

3. The combination with a furnace and side chambers, of the tier of water tubes having the lower ends of each row of tubes connected together and with the side chambers, each row communicating with said side chambers independently of the other rows, the upper portions of the tubes being extended uprightly to the inclined portions of the tubes and connected with a steam chamber or drum communicating with the steam distributing

pipe, substantially as and for the purposes described.

4. The combination with the furnace, of the tier of inclined water tubes having their upper portions extended at an angle to the inclined portions, the T's P coupled together at opposite ends of each row of the tier of tubes and having the tubes communicating therewith, and the T's R and V at the opposite ends of the tubes to one side thereof respect-

ively coupled together and having the T's P at the ends of the tubes communicating therewith, substantially as and for the purposes described.

In testimony whereof I affix my signature in presence of two witnesses.

RALPH BROOKS VAUGHN.
